HOT TOP CASING

Geoffrey Fenton, Lakewood, Ohio, assignor to Foseco International Limited, Nечells, England, a British company

Continuation of design applications Ser. No. 4,974, Dec. 8, 1966, and Ser. No. 5,465, Jan. 18, 1967. This application Oct. 18, 1967, Ser. No. 9,151

Term of patent 14 years

(Cl. D54—8)

FIG. 1

FIG. 2

FIG. 3

FIG. 4

FIG. 5

FIG. 6

FIG. 7

FIG. 8

FIG. 9

FIG. 10

FIGURE 1 is a bottom perspective view of a hot top casing embodying the design of this invention;

FIG. 2 is a bottom plan view of the hot top casing of FIG. 1;

FIG. 3 is a side elevation view of the hot top casing of FIG. 1;

FIG. 4 is an end elevation view of the hot top casing of FIG. 1;

FIG. 5 is a top plan view of the hot top casing of FIG. 1;

FIG. 6 is a perspective view of a modified hot top casing embodying the design of this invention;

FIG. 7 is an exploded perspective view of the hot top casing of FIG. 6;

FIG. 8 is a top plan view of the hot top casing of FIG. 6;

FIG. 9 is a front elevation view of the hot top casing of FIG. 6;

FIG. 10 is a side elevation view of the hot top casing of FIG. 6; and

FIG. 11 is a bottom plan view of the hot top casing of FIG. 6.

The dominant features of my design reside in the portions shown in full lines.

This application is a continuation of my applications Ser. No. D.4,974, filed Dec. 8, 1966, entitled "Hot Top Casing," now abandoned and Ser. No. D.5,465, filed Jan. 18, 1967, entitled "Hot Top Casing," now abandoned.

I claim:

The ornamental design for a hot top casing, substantially as shown and described.
